CLAIM

The ornamental design for a head for a gum massager,
as shown and described.

DESCRIPTION

FIG. 1 is a front elevational view of a gum massager
head, showing my new design;

FIG. 2 is a rear elevational view thereof;

FIG. 3 is a right side elevational view thereof, the left
side elevational view being identical thereto;

FIG. 4 is a top plan view thereof;

FIG. 5 is a bottom plan view thereof;

FIG. 6 is a front elevational view of a second embodi-
ment of the gum massager head;

FIG. 7 is a rear elevational view thereof;

FIG. 8 is a right side elevational view thereof, the left
side elevational view being identical thereto;

FIG. 9 is a top plan view thereof; and,

FIG. 10 is a bottom plan view thereof.

The broken line showing of the handle in FIGS. 1-10 is
for illustrative purposes only and forms no part of the
claimed design.

FIG. 1

FIG. 2

FIG. 3

FIG. 4

FIG. 5

FIG. 6

FIG. 7

FIG. 8

FIG. 9

FIG. 10
